UNITED STATES PATENT OFFICE

CHARLES E. CONNER, OF TORRANCE, CALIFORNIA

DISPENSING DEVICE

Application filed April 8, 1931. Serial No. 528,607.

This invention relates to a dispensing device which is adapted to dispense various small articles, more particularly toothpicks or matches.

5 An object of the invention is to provide a dispensing device of the character stated which combines with the magazine and inclined feed floor thereof, an improved detachable cover which can be manufactured at 10 a low cost and which is furnished with exceedingly simple means for removably maintaining it in the closed position.

More specifically stated the invention pertains to a magazine having a cover which is 15 releasably held in place by means of an improved arrangement of locking shoulders, resilient lug and a depression wherewith said lug cooperates to yieldingly maintain the cover in the closed position after said cover 20 has been forced into place with said lug seated in said depression.

Other objects, advantages and features of invention may hereinafter appear.

Referring to the accompanying drawing 25 which illustrates what is at present deemed to be a preferred embodiment of the invention,

Fig. 1 is a plan view of the device showing the cover in place and showing combined 30 therewith a coin tray.

Fig. 2 is a side elevational view of Fig. 1.

Fig. 3 is a front elevation.

Fig. 4 is a fragmentary sectional view taken through the locking shoulders which aid in 35 holding the cover in place, on line 4—4 of Fig. 2.

Fig. 5 is a cross-section of the cover taken on the same plane as Fig. 4, the central portion of the cover being broken away to contract the view.

Fig. 6 is a section on line 6—6 of Fig. 4, but differs from the latter view in that an elastic lining is shown within the seat which is engaged by the boss carried by the lid.

45 Fig. 7 is a cross-section on line 7—7 of Fig. 5, but differs from Fig. 5 in that a resilient washer is shown placed around the boss carried by the lid.

Referring in detail to the drawing, the receptacle is provided with a magazine portion

9 and a cover portion 10, and by preference and as shown, is also provided with a lateral extension 11 having a side portion 12 and walls 13 and 14 in order to form a tray to receive coin or for other purposes.

55 The magazine 9 is provided with side portions 15 and 16 and with a floor portion 17, said portions 15, 16 and 17 all being inclined in order to direct the articles contained within the magazine downwardly to the retaining 60 lip 18 which is placed at the lower or floor end of the device. The cover 10 is provided with the side portions 20 and 21, with the back wall 22 and with the semi-circular notch 23 at its lower end, said notch 23 cooperating 65 with the notch 24 of the base portion of the receptacle in order that matches, toothpicks or the like may readily be removed by the fingers.

70 Describing the means for releasably holding the cover in place, at each side of the magazine is provided a notch or recess 25, and at each side of the cover is provided an inwardly directed boss 28 which cooperates with said recess 25. As well shown in Fig. 4, said notch 75 25 extends into the side wall of the receptacle only about half way therethrough. Said notch, furthermore, is provided near its base with a slight offset 25a which forms a seat for the boss 28 to cooperate effectively with 80 said boss 28 to hold the cover in place.

At the other end of the cover there is provided, within the back wall 22, an inwardly directed socket 27 within which is secured the elastic plug 28a, the inwardly projecting 85 end of which is preferably rounded as shown to lock the cover in place.

In Fig. 6 is shown a modification wherein the recess or notch 25 is lined with a rubber or like strip 35, the resilient nature of which aids in releasably holding the cover in place.

90 In Fig. 7 is shown another modification wherein the boss 28 has slipped thereover a sleeve 40 of rubber or other resilient material which likewise cooperates with the locking 95 means to keep the cover releasably in place.

In Figs. 4, 5 and 6 a piece of cardboard 55 is shown pasted to the under side of the cover 10 to illustrate the position of the cardboard which will be used in some instances as a 100

means of displaying advertising matter through the cover when the same is made of a transparent material.

I claim:

- 5 1. In a device of the kind described, in combination, a cover having a flange extending around three sides thereof, one of said flanges being located at an end of said cover and having a resilient boss projecting from its inner face, and each of the other flanges having near the other end of the cover an internally projecting boss; and a receptacle upon which said cover fits, said receptacle having a depression at one end with which said resilient boss cooperates and having near its other end a recess formed in each outer side thereof to cooperate with said internally projecting bosses.
- 10 2. In a device of the kind described, in combination, a cover having a flange extending around three sides thereof, one of said flanges being located at an end of said cover and having a resilient boss projecting from its inner face, and each of the other flanges having near the other end of the cover an internally projecting boss; and a receptacle upon which said cover fits, said receptacle having a depression at one end with which said resilient boss cooperates and having near its other end a recess formed in each outer side thereof to cooperate with said internally projecting bosses, said recesses consisting of grooves which are provided with offset portions to cooperate more effectively with said internally projecting bosses.

In testimony whereof I hereunto affix my signature.

CHARLES E. CONNER.
